(57) **CLAIM**

The ornamental design for a beverage container with removable bottle opener, as shown and described.

DESCRIPTION

FIG. 1 is an exploded view of a beverage container with removable bottle opener of the present design;

FIG. 2 is a front view of the beverage container with removable bottle opener of the present design, the rear view and side views being identical thereto;

FIG. 3 is a top view of the beverage container with removable bottle opener of the present design;

FIG. 4 is a bottom view of the beverage container with removable bottle opener of the present design, wherein the removable bottle opener is mounted on the bottom of the beverage container;

FIG. 5 is a front perspective view of the beverage container with removable bottle opener of the present design;

FIG. 6 is a bottom perspective view of the beverage container with removable bottle opener of the present design;

FIG. 7 is a bottom perspective view of the removable bottle opener of the present design without the beverage container;

FIG. 8 is a bottom view of the removable bottle opener of the present design;

FIG. 9 is a top view of the removable bottle opener of the present design; and,

FIG. 10 is a front view of the removable bottle opener of the present design, the rear view and side views being identical thereto.

In the drawings, the broken lines show screw threads, the thickness of the container, and certain indentations in the base that form no part of the claim.

1 Claim, 10 Drawing Sheets
